UNITED STATES PATENT OFFICE.

WALTER K. TRECHSEL, OF BIRMINGHAM, ALABAMA.

DESIGN FOR A COUPON-BOOK.

56,842.

Specification for Design. Patented Dec. 28, 1920.

Application filed April 23, 1919. Serial No. 292,178. Term of patent 14 years.

To all whom it may concern:

Be it known that I, WALTER K. TRECHSEL, a citizen of the United States, residing at Birmingham, in the county of Jefferson and State of Alabama, have invented a new, original, and ornamental Design for Coupon-Books, of which the following is a specification, reference being had to the accompanying drawing, forming a part thereof.

The figure is a plan view of a coupon book, showing my new design.

I claim:

The ornamental design for a coupon book, as shown.

WALTER K. TRECHSEL.
